UNITED STATES PATENT OFFICE.

CHARLES J. SEARLES, JR., OF VICKSBURG, MISSISSIPPI.

LIQUID-HEATER.

1,200,766.

Specification of Letters Patent.

Patented Oct. 10, 1916.

Application filed May 14, 1915. Serial No. 28,148.

To all whom it may concern:

Be it known that I, CHARLES J. SEARLES, Jr., a citizen of the United States, residing a Vicksburg, in the county of Warren and State of Mississippi, have invented certain new and useful Improvements in Liquid-Heaters, of which the following is a specification.

My invention relates to heaters, and more particularly to an improved electric heater capable of detachable connection with a faucet whereby to heat liquid issuing therefrom.

The primary object of my invention is to provide a heater of the above class which is simple in construction, cheap to manufacture, strong, and durable and one which is easily attached and detached from a faucet.

Another object of my invention is to provide improved means for mounting the heating elements, as well as the manner of association with the liquid conducting member.

A still further object of my invention is to provide means whereby to ventilate the heater while in use so as to prevent burning out of the heating elements.

With the above and other objects in view my invention resides preferably in the construction, combination, and arrangement of parts as hereinafter set forth in the specification and illustrated in the accompanying drawing, in which

Figure 1 is a vertical sectional view of a heater embodying the improvements of my invention. Fig. 2 is a transverse sectional view taken on the line 2—2 of Fig. 1. Fig. 3 is a bottom plan view of my invention.

Similar reference characters indicate similar parts throughout the various views of the drawings.

Referring more particularly to the drawings in which the preferred embodiment of my invention is illustrated, I provide a casing 1 threaded externally at its opposite extremities as indicated at 2 and 3 to receive end caps 4 and 5 respectively.

The end cap 4 is substantially frusto-conical in configuration and is provided with a threaded aperture 6, which aperture tapers as at 7 to provide a reduced threaded portion 8 for a purpose which will hereinafter appear. A connecting member is provided which comprises a bar 9 having a projecting sleeve 10 intermediate its length provided with an aperture 11, said projecting sleeve 10 being threaded for engagement with the

threaded opening 6 in the cap 4. A suitable washer 12 of rubber or the like is mounted in the aperture 11 to facilitate engagement of the connecting member with a faucet. 60 The bar 9 is extended and curved on its opposite extremities to provide handles 13 for an obvious purpose. A wire gauze strainer 14 is provided in the inlet aperture 11 and is retained therein by the projecting sleeve 65 10. The cap 4 is provided with an annular internally threaded flange 15 for engagement with the screw threaded portion 2 of the casing 1.

On the opposite extremity of the casing 70 1 from that on which the cap 4 is mounted 1 provide a cap 5 substantially hemi-spherical in contour, said cap 5 being recessed to provide an annular shoulder 17 and a flange 18, which flange 18 is threaded internally 75 for engagement on the threaded portion 3 of the casing 1. The cap 5 is further provided with an annular recess 19, which recess communicates with the outer surface of the cap 5 by means of radially extending apertures 80 20 for the purpose of ventilation. An outlet aperture 21 having a threaded portion 22, a flaring portion 23, and a reduced portion 24 is formed in the cap 5 and located substantially concentric with said cap as 85 shown to advantage in Fig. 1. An outlet nozzle 25 is provided, externally threaded for engagement in the threaded portion 22 of the opening 21, and contains a plurality 90 of wire gauze strainers 26.

The heating elements of my invention are disposed within and longitudinally of the casing 1, said casing having a plurality of supplemental inner casings disposed therein providing annular chambers in which the 95 heating elements are disposed. The casings mentioned are designated 27, 28 and 29, said casings being disposed one within the other and in this instance supporting a liquid conducting member and the heating elements. It is to be understood that while three of these casings have been shown, the 100 number of the same may be varied.

The containers for the heating elements of my invention comprise a plurality of tubular members 30, being lined as at 31 with insulating material such as asbestos, rubber or the like. The heating elements comprise coils of wire of some metal having a high resistance coefficient, such as German silver or the like, and are designated 32. Tubular members are mounted in space 110 relation in

the annular chambers provided by the outer casing 1 and the casing 27 and the two inner casings 28 and 29 as shown to advantage in Fig. 2. The annular chamber between the 5 casings 27 and 28 is utilized in the present instance for the liquid conducting member which comprises a coil 33, the convolutions of which are placed about the casing 28 as shown to advantage in Fig 1, the opposite 10 extremities of said coil being connected to the inlet and outlet openings in any suitable manner, these extremities being designated 34 and 35.

The casing 1 is lined internally with asbestos or the like as indicated at 36 for an 15 obvious purpose, this not only serving to retain the heat within the casing 1 but preventing the outer surface of the casing itself from becoming heated during operation.

20 The heating elements 32 are connected in series by means of conductors 37 in this form of my invention. However, it is to be understood that the peculiar connection of the heating elements does not necessarily enter into the present invention. The terminals of the heating means are designated 39 and 40 and are mounted on an insulating plate 41 disposed at one end of the casing 1. A plurality of electric conductors, which are 25 connected to some source of electric energy, are designated 42 and pass through an insulating bushing 43 disposed in the cap 4, said conductor being connected to the binding post or terminals 39 and 40 in any appropriate way. The cap 4 is provided with a 30 ventilating opening 44. In order to insulate the heating elements and their containers from the end cap 5 I provide an insulating plate 45 disposed in said cap and against 35 which the containers 30 are adapted to engage. Suitable ventilating openings 46 are provided in the plate 45, these openings allowing air to circulate in contact with the coil 33 whereby to assist in the heating operation and quickly cool the coil when not in use. The openings 46 also allow liquid to escape through the openings 20 should there be any leak in the coil 33. The innermost 40 casing 29 may be used as a ventilating duct 45 or may be provided with heating members.

From the above description taken in connection with the accompanying drawings, it is thought that a clear and comprehensive understanding of the construction, operation, and advantages of my invention may be gathered. It will be noted that in using the device it is only necessary to connect the 55 same to the faucet and turn on the electric current. By opening the faucet, water or

similar liquid will be allowed to flow 60 through the tube 33, and it will instantaneously become heated and pass out through the nozzle 25 at any temperature desired, it being, of course, understood that a controlling rheostat may be provided for increasing 65 or decreasing the heat generated by the heating elements. Any liquid which may leak from the tube 33 will be conducted downwardly through the apertures 46 to the chamber 19 and thence through the openings 70 20 to the outer face of the cap 5 thereby indicating that there is a leak. Of course, it will be understood that the device may be operated even though the tube should leak, since the insulating plates 41 and 45 are secured in a water tight manner to the containers 30 and casings 1, 27, 28 and 29. 75

While I have shown and described my invention as possessing a peculiar form and construction, it is desired that it be understood that I may make such changes in the details thereof that do not depart from the spirit and scope of the invention as claimed. 80

Having thus described my invention what I claim and desire to secure by Letters Patent is:

1. A liquid heater, including an outer casing, a plurality of concentrically arranged supplemental casings therein providing annular chambers, heating elements in the outermost and innermost of said chambers, and a coiled conduit disposed therebetween and communicating with a liquid supply. 90

2. A liquid heater, including an outer casing, a plurality of concentrically arranged supplemental casings therein providing annular chambers, heating elements in the outermost and innermost of said chambers comprising tubular members disposed longitudinally of the casing, and liquid conducting 100 means between said heating chambers. 95

3. A liquid heater, including, in combination, an outer casing, a plurality of concentrically arranged supplemental casings therein providing annular chambers, end caps for said casing having a coiled conduit carried thereby and disposed in one of the chambers, and longitudinally arranged heating elements in certain other of the chambers inside and outside of the conduit and in 110 spaced relation thereto to permit ventilation. 105

In testimony whereof I affix my signature in presence of two witnesses.

CHARLES J. SEARLES, JR.
